UNITED STATES PATENT OFFICE.

EMILIO FONTQUERNI-VILA, OF NEW YORK, N. Y.

WINDOW-CONTROLLING DEVICE.

1,348,275.

Specification of Letters Patent.

Patented Aug. 3, 1920.

Application filed March 29, 1918. Serial No. 225,599.

To all whom it may concern:

Be it known that I, EMILIO FONTQUERNI-VILA, a citizen of the United States, residing at New York, in the county of New York, 5 State of New York, have invented certain new and useful Improvements in Window-Controlling Devices; and I do hereby declare the following to be a full, clear, and exact description of the invention, such as will enable 10 others skilled in the art to which it appertains to make and use the same.

The present invention relates to new and useful improvements in devices for opening or closing windows or doors, and it is more 15 particularly directed to the provision of such a device operable from a point remote from the window or door to be actuated. It is in general the object to simplify and otherwise improve the structure and to increase 20 the efficiency and ease of operation of devices of this character, and it is more particularly an object in this connection to provide an operating device for windows which may be associated with the ordinary frame 25 and sashes of a window in a most ready manner.

A further and important object resides in the provision of an arrangement wherein the window or other member to be operated is 30 locked against movement in either direction except during its movement by said actuating means.

A still further object resides in the provision of a device of the present nature 35 whose operation may be electrically controlled from a point remote from the member to be moved, whereby said windows or the like may be simultaneously closed upon the occurrence of storm or for any other reason.

With the above and other objects and advantages in view, the invention resides more particularly in the novel combination, formation and arrangement of parts herein- 40 after described and particularly pointed out in the appended claims.

In the accompanying drawings:

Figure 1 is a front elevational view of a window operating device embodying the 45 present invention and associated with a window of conventional type, the front portion of the window frame being broken away to more clearly disclose the structure.

Fig. 2 is a sectional view taken vertically on the line 2—2 of Fig. 1.

Fig. 3 is a sectional view taken hori-

zontally through the operating shaft and clutch mechanisms.

Fig. 4 is a transverse sectional view on the line 4—4 of Fig. 1.

Fig. 5 is a fragmentary sectional view on the line 5—5 of Fig. 1, and showing one of the circuit breaking switches operated by the sash frames, and

Fig. 6 is a wiring diagram for the device.

Fig. 7 is an enlarged detail sectional view of the extension sections of the motor shaft and casing.

Fig. 8 is a detail section taken longitudinally of one of the clutch sleeves.

Referring now more particularly to the accompanying drawings, 5 designates generally a window frame in which is slidably mounted the upper and lower sash members 6 and 7 respectively, the sash frame being 75 of generally conventional nature, providing spaces of conventional nature between its inner side walls and the building structure, said spaces being usually employed as wells for the sash weights.

In embodying the present invention, I provide a pair of hanger brackets 8 in each upper corner of the window frame, and each hanger bracket carries a shaft 9 on which is mounted a pair of idle sprocket wheels 10 85 about which are trained a pair of outer and inner sprocket chains 11 and 12 respectively, each of these chains being endless in nature and there being thus a pair of chain belts at each side of the sashes. The corners of 90 the upper sash 6 are secured to the outer chain belts 11 by outwardly projecting bracket arms 13 while the lower sash is secured to the inner chains 12 by relatively shorter outwardly projecting bracket arms 95 14 at its four corners, the bracket arms 13 and 14 extending through slots in the inner side walls of the window frame whereby said sash members may have sliding movement throughout the vertical length of the 100 frame.

For operating these chains to control the positions of the sashes, a motor casing 15 is mounted under the central portion of the frame and has casing sleeves 16 extending 105 longitudinally from its sides in which is mounted the motor shaft 17 carrying the armatures of a pair of motors 17^a and 17^b arranged to run in opposite directions. Journaled in a suitable supporting and bearing member 18 at the outer end of one of the casing sleeves 16, and disposed in axial aline-

ment with the sleeve is the hub 19 of a sprocket wheel 20 about which is trained the lower end of the inner chain belt 12 at the corresponding side of the window frame. 5 Journaled in the hub 19 and in a bearing bracket 21 disposed outwardly thereof is the shaft of an idle sprocket wheel 23 about which is trained the adjacent outer chain belt 11. The inner chain belt 12 at the other 10 side of the frame is trained about a sprocket wheel 24 idly mounted on the outer end of the adjacent casing sleeve 16, and the lower end of the outer chain belt 11 is trained about a sprocket wheel 25 whose hub is in 15 axial alinement with the casing sleeves 16 and is journaled in a bearing bracket 26. The motor shaft 17 extends outwardly of the end of the sleeve casings 16 into squared recesses 27 in the hubs of the sprocket wheels 20 and 25. Thus by clutching the shaft to either of the sprocket wheels, the corresponding chain belts may be actuated by operation of the motor to move either window. 20

25 The clutch mechanisms for accomplishing this comprise a pair of clutch sleeves 28 and 28^a respectively splined on the end portions of the motor shaft 17 and having their outer faces squared to engage slidably in 30 the squared recesses 27 of the sprocket wheels 20 and 25 respectively and in the squared recesses 30 in the outer ends of the sleeve casings 16. The clutch members are each provided with a central annular groove 31, in 35 which is engaged the upturned spanner arms 32 at the end of a single actuating rod 33 which extends parallel to the engine shaft and casing sleeves, being normally urged to a position wherein the clutch sleeves 28 and 40 28^a are held between the sprocket wheel hubs and casing sleeve ends by springs 35 secured to the rod and to later described solenoids 36 and 37 in which the rod is slidably mounted. With each of the clutch sleeves 45 held in this position its squared portions engage in both the squared recesses 27 and 30 and thus hold the sprocket wheels 20 and 25, preventing rotation of the wheels in either direction to lock the sashes in any positions which they may assume. To actuate 50 said clutch members to operate the window sashes the solenoid coil 36 surrounds the rod adjacent the sprocket wheel 20 and the solenoid 37 surrounds the rod adjacent the 55 sprocket wheel 25, these solenoids being adapted upon energization to shift the rod in either direction. Upon said shifting movement of the rod toward the sprocket wheel 20 for instance, the clutch sleeve 28 will disengage from the recess 30 of the casing section 16 and will move farther into the recess 27 of the sprocket wheel 20. At the same time, the clutch sleeve 28^a will move away from the recess 27 of the sprocket wheel 25 60 65 and its squared portion adjacent the casing

sleeve 16 will move into a cylindrical inner portion of the recess 30 of said casing sleeve, whereby rotation of the motor shaft is permitted, the sprocket wheel 25 being idle. Thus driving rotation of the motor shaft 19 70 in either direction will raise or lower the sash 7 and upon shifting movement of the rod 33 in an opposite direction effected by the solenoid 37, the upper sash may be moved in a similar manner. 75

An exceedingly simple structure has thus been provided which affords absolute control for movement of the sashes and the window or any other shiftable members, and it is noted that the present device may be associated with an ordinary window frame in a most ready manner. The chain belts at both sides of the sashes assist in procuring a proper sliding movement thereof, and the sashes, when their controlling sprockets are 80 released, are held against undesired sliding movement by friction, or by sash weights 39 secured to the belt stretches opposite those to which the bracket arms 13 and 14 are secured, it being obvious however, that 85 a single chain may be employed for each sash. 90

As shown in the diagram Fig. 6 there is a source of electricity illustrated as a generator 44, which is electrically connected 95 by means of a wire 43 with both of the motors 17^a and 17^b. Between the motor 17^a and the solenoid 37 there is an electrical connection 41, including a pair of switches 50 and a third switch 45, connected in series, and between the motor 17^b and the solenoid 36, there is a similar connection 42 including two switches 50 and a third switch 48, also connected in series, the switches 45 and 48 lying between the switches 50 and 100 105 the respective solenoids. A wire 43^b, in circuit with which there is a switch 46, connects the solenoid 37 with the connection 42 between the switches 48 and 50, while a wire 43^c, having a switch 47 in circuit therewith 110 connects the solenoid 36 with the connection 41 between the switch 45 and the switches 50. Both of the solenoids are grounded with the generator as indicated at 43'. From the foregoing it will be seen that 115 either solenoid may be connected in series with either motor. 120

In the assembled apparatus, the switches 50 are located one at each limit of movement of each sash, and, as illustrated in Fig. 5, they are constructed so as to be engaged and opened by projections 51 on the sashes, so that when the sashes have reached the limit of their movements the circuits in which these switches are included will be 125 broken.

Referring again to Fig. 6, it will be seen that with the switches 50 in the connection 41 closed and the switches 46, 47 and 48 open, the switch 45 may be closed, when 130

current will flow from the generator 44, through the wire 43 to the motor 17^a; thence through the connection 41 to the solenoid 37, through the latter and back through the 5 ground 43' to the generator.

With the switches 45, 47 and 48 open and the switch 46 closed, current will flow from the generator through the wire 43 to the motor 17^b, thence through the connection 10 42, the switches 50 therein being closed, to and through the wire 43^b to the solenoid 37 and thence through the ground 43' to the generator.

With the switch 47 closed and the 15 switches 45, 46 and 48 open, current will flow from the generator through the wire 43 to the motor 17^a, thence through the connection 41 to and through the wire 43^c to the solenoid 36, and thence through the 20 ground 43' to the generator.

With the switch 48 closed and the switches 45, 46 and 47 open, current will flow from the generator through the wire 43 to the motor 17^b, thence through the connection 25 42 to the solenoid 36 and finally from this solenoid through the ground to the generator.

The switches 45, 46, 47 and 48 thus may be termed operating switches, the switches 30 45 and 46 controlling the movement of the one of the sashes, while the switches 47 and 48 control the movement of the other sash.

It will be further understood that the 35 motor may be placed at any desired point in the arrangement shown, and that the shaft 17 which in the present arrangement forms the armature shaft of the motor, may be utilized simply as a power transmission shaft.

40 It is further obvious that inasmuch as one important feature of the invention resides in the provision of the novel locking clutch connections between this power transmission shaft and stationary parts of the 45 apparatus, any means other than an electrical motor may be employed for imparting power to the apparatus and the solenoids may be operated by electrical circuits independent of any other function. To render 50 the device adjustable for various sizes of windows, the lengths of the chains may be varied with respect to varying heights of the windows and the shaft and casing 16 and 17 may be provided with extension por-

tions 55 compensating for varying widths 55 of windows.

While the apparatus has been described as embedded in the window frame, it may obviously be positioned at the outside of an ordinary window frame, its position 60 within the frame however being procurable with existing window structures as heretofore set forth.

While I have shown my device as associated with a window for procuring vertical 65 closing movement of the sashes thereof, it is obvious that the device may act to move closure members either vertically or horizontally.

While I have shown and described a preferred embodiment of my invention, it is obvious that various other changes and modifications of structure and arrangement may be resorted to meet the different conditions of use without departing in any manner from the spirit of the invention, as defined by the accompanying claims.

What is claimed is:

1. A device of the class described comprising a drive shaft, a pair of drive members, a pair of stationary locking members, clutch members splined on the shaft, a rod connecting said clutch members, means normally urging said clutch members to clutching engagement with both the drive members 80 and locking members and means for shifting said rod to disengage the clutch members from clutching relation with the locking members and with one of the drive members.

2. A device of the class described including a drive shaft, a drive member, a locking member, a clutch splined on the drive shaft and normally in engagement with said drive and locking member, a slid able rod connected with said clutch for operating it, means resiliently urging said rod to position holding the clutch in engagement with the drive and locking members and a solenoid coil on said rod for shifting it to disengage 95 the clutch from the locking member.

In testimony whereof I affix my signature, in the presence of two witnesses.

EMILIO FONTQUERNI-VILA.
